UNITED STATES PATENT OFFICE.

SAMUEL A. ULRICH, OF MENDOTA, MISSOURI.

GEARING FOR STRETCHERS.

1,080,503.

Specification of Letters Patent.

Patented Dec. 2, 1913.

Application filed February 25, 1913. Serial No. 750,614.

To all whom it may concern:

Be it known that I, SAMUEL A. ULRICH, a citizen of the United States, residing at Mendota, in the county of Putnam and State 5 of Missouri, have invented certain new and useful Improvements in Gearing for Stretchers, of which the following is a specification, reference being had therein to the accompanying drawing.

10 This invention relates to wire stretchers and has for its object the production of an efficient device for stretching wire.

Another object of this invention is the production of a novel means for rotating the 15 drum of the wire stretcher.

With these and other objects in view this invention consists of certain novel combinations, constructions and arrangements of parts as will be hereinafter fully described 20 and claimed.

Reference is to be had to the accompanying drawing forming a part of this specification in which similar letters of reference indicate corresponding parts in all figures.

25 Figure 1 is a front elevation of an improved wire stretcher in use. Fig. 2 is a section taken on line 2—2, Fig. 1. Fig. 3 is a section taken on line 3—3, Fig. 2. Fig. 4 is a sectional view of the winding drum.

30 Fig. 5 is a perspective view of the brace used in connection with the bearings for the worm gear. Fig. 6 is a perspective view of the yoke that substantially holds the forward ends of the body of the stretcher together. Fig. 7 is a transverse section taken 35 on line 9—9, Fig. 1.

Referring to the accompanying drawing by reference numerals, this wire stretcher consists of side plates 10 and 11 which have 40 positioned intermediate their length a brace 12 and a bracing rod 13 adjacent their rear ends. A securing yoke 14 is secured to the front end of the sides of this wire stretching device to securely hold the front end of the 45 wire stretcher together.

Mounted upon the axle 16 is a winding drum 15 which is provided with link receiving pockets 17 and has an integral gear wheel 18 positioned on one end. A spacing 50 collar 19 is mounted upon the axle 16 between the integral gear wheel 18 and the inner face of the side bar 10 to hold the integral gear wheel 18 and the drum 15 in the desired position.

55 Secured to the intermediate brace 12 by an eye bolt 20 is a standard 21 which is

made integrally with a cylindrical bearing 22. A shaft 23 passes through this bearing 22 and has on its outer end a worm gear 24 which is adapted to mesh with the integral gear wheel 18 of the winding drum 15. A brace 25 is secured to the cylindrical bearing as shown at 26 and has an angle foot 27 at its lower end which has a securing means passing through and engaging the side bar 60 65 10. This brace holds the cylindrical bearing in a firm position thus keeping the worm gear 24 always in engagement with the teeth of the integral gear wheel 18. The standard 21 has its bottom end reduced as 70 shown at 28 to form a shoulder 29 which shoulder fits snugly against the upper face of the intermediate bracing member 12. By this construction the cylindrical bearing 22 is held against any movement. 75

On the rear end portions and on their upper faces of the side plates 10 and 11 there are positioned bearings 29 and 30 which have an axle 31 passing through them. Mounted upon this axle 31 is a bevel gear 32 which is adapted to engage a gear wheel 33 which is placed upon the inner end of the shaft 23. A handle 34 is mounted upon one end of the axle 31 to provide means for the rotation of the bevel gear 32. 85

In operation of this device a chain 35 is secured to the eye bolt 20 and has its free end secured to a tree or any convenient means, and a chain 36 engages the clamp of the wire fence to be stretched and has its 90 free end in engagement with the drum 15. The device being now in position all that is necessary is to rotate the handle 34 which, of course, rotates the bevel gear 32 which winds the drum 15 by means of the gear 95 wheel 33, the worm gear 24 and the integral gear wheel 18. As the drum is provided with the link receiving pockets 17, the links will fit snugly in these pockets, and will, of course, pull the wire toward the stretcher. 100

It is obvious that minor changes may be made in the form and construction of the invention without departing from the material principles thereof, and it is therefore not wished to confine the invention to the exact form herein shown and described, but it is wished to include all such as properly come within the scope claimed.

Having thus described the invention what is claimed as new, is:—

1. A device of the character described comprising side bars, bracing means con-

- necting said side bars, a drum rotatably mounted between said side bars, said drum being provided at one end with an integral gear wheel, a standard secured to one of said 5 bracing members, a bearing formed at the upper end of said standard, a shaft passing through said bearing and having a worm gear at its forward end, said worm gear meshing with the gear wheel of said drum, 10 bracing means for said bearing for holding said worm gear in engagement with said gear wheel, and operating means secured to said side bars for rotating said shaft.
2. A device of the character described 15 comprising a plurality of side bars, bracing members positioned between said side bars, a drum rotatably mounted between said side bars, an integral gear wheel formed at one end of said drum, an upright standard 20 mounted upon one of said bracing members, a cylindrical bearing made integral with said standard at its upper end, a shaft pass-

ing through said cylindrical bearing and having a worm gear positioned at one end, a brace provided with an angle foot at its 25 lower end, said angle foot engaging one of said side bars, said brace having its upper end bent so as to fit snugly against the outer face of said cylindrical bearing, operating means mounted upon the rear end portion of 30 said side bars, a gear wheel mounted upon the rear end of said shaft mounted in said cylindrical bearing, said operating means rotating said worm gear by engagement with said gear wheel, said worm gear rotating 35 said drum by means of its engagement with said integral gear wheel positioned at one end of said drum.

In testimony whereof I hereunto affix my signature in presence of two witnesses.

SAMUEL A. ULRICH.
